COMBINED HOSTESS TRAY AND TUMBLER HOLDER

James B. Swett, Barrington, R.I., assignor to Rexall Drug and Chemical Company, Los Angeles, Calif., a corporation of Delaware

Filed Nov. 16, 1961, Ser. No. 67,551

Term of patent 14 years

(Cl. D44—10)

FIGURE 1 is a view in perspective of a combined hostess tray and tumbler holder showing my new design; FIGURE 2 is a view in elevation of the same; and FIGURE 3 is a view on the line 3—3 of FIGURE 2 of the same.

I claim:

The ornamental design for a combined hostess tray and tumbler holder, as shown.
